(74) *Attorney, Agent, or Firm* — Reed Smith LLP;
Matthew P. Frederick

(57) **CLAIM**

The ornamental design for a surgical drape, as shown and described.

DESCRIPTION

FIG. 1 is a perspective view of a top side of a surgical drape in accordance with my new design;

FIG. 2 is a perspective view of a bottom side thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partial detail view taken from the section indicated as 9 in FIG. 3;

FIG. 10 is a partial detail view taken from the section indicated as 10 in FIG. 1; and,

FIG. 11 is a partial detail view taken from the section indicated as 11 in FIG. 2.

The dashed lines in the figures depict portions of the surgical drape that form no part of the claimed design. The dot-dash lines in the drawings depict the boundaries of the enlarged views that form no part of the claimed design.

1 Claim, 9 Drawing Sheets
